Primary Examiner — Marissa J. Cash*Assistant Examiner* — Kayla Marie Bennett*(74) Attorney, Agent, or Firm* — Renner, Otto, Boisselle & Sklar, LLP(57) **CLAIM**

The ornamental design for a bracket, as shown and described.

DESCRIPTION

FIG. 1 is a front perspective view of a bracket showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The uniform broken line showing in FIGS. 1-7 is for the purpose of illustrating portions of the bracket and forms no part of the claimed design.

1 Claim, 6 Drawing Sheets(56)
